UNITED STATES PATENT OFFICE.

JOHN E. MILLER, OF HUNTINGTON, WEST VIRGINIA.

DENTAL FORCEPS.

Application filed March 26, 1927. Serial No. 178,752.

This invention relates to improvements in dental forceps and more particularly to a device of this character which may be universally employed in the extraction of teeth or roots of teeth and which is so constructed that it will not lacerate the jaw in the extracting operation.

A further object of the invention is to produce a device of this character so constructed that a maximum strain may be exerted to extract the tooth at the expenditure of a minimum amount of energy on the part of the operator and without danger of splitting the engaged tooth.

15 A further object of the invention is to produce forceps of the "cow-horn" type, the jaws of which are at all times spaced from one another and are so constructed that they will firmly engage the tooth, these jaws being so related to the forceps handle that they may be conveniently engaged with any tooth in the head and efficiently employed in the extraction of the same, without regard to whether the tooth must be rotated in extraction.

These and other objects I attain by the construction shown in the accompanying drawings, wherein for the purpose of illustration is shown a preferred embodiment of 20 my invention and wherein:—

Figure 1 is a side elevation of forceps constructed in accordance with my invention;

Figure 2 is an edge elevation thereof;

Figure 3 is an enlarged plan view partially in section of the jaws of the forceps;

Figure 4 is a fragmentary detail sectional view taken on the line 4—4 of Figure 3.

Figures 5 to 10 show the forceps in use.

Referring now more particularly to the 40 drawings, the numerals 10 and 11 indicate plier connected elements, each formed at one end with a handle and at the opposite end with a curved and tapered jaw 12. The jaws 12 are reverse duplicates of one another and

45 are similar to the "cow-horn" type of forceps jaw, with the exception of the fact that these jaws are more bluntly tapered than the ordinary jaw of this type and are provided with sharp points 13 at their free ends.

50 The space 14 between the jaws is likewise made of greater size than that ordinarily provided between the extremities of jaws of this type. These jaws, as more clearly shown in Figure 2, are disposed at an angle 55 of approximately 45° to the general plane of the handle portions of the members 10

and 11. It is to be particularly noted that the longitudinal axes of the jaws 12 are straight from end to end and in parallelism thereby assuring an effective leverage action in all operations of the forceps with the elimination of any liability of inward or outward motion or rotatable motion with respect to the tooth being operated upon. The handle portion of the member 11 at that end thereof next adjacent the pivotal connection 15 is preferably extended in the general direction of the axis of the tool.

The terminal or free end of this handle, as indicated at 16, is deflected across the axis 70 of the tool at an angle of approximately 30° thereto. The handle portion of the member 10 adjacent the pivot thereof is deflected in the same direction as this terminal portion, so that it substantially parallels the same, as 75 at 17, and the terminal portion 18 thereof, which is provided with a hand rest hook 19, is extended in the general direction of and parallel to the axis of the tool and when the points 13 of the jaws are most nearly adjacent one another, is in contact with the terminal portion 16 of the handle of the member 11. By arrangement of the handles in this way, a maximum convenience in manipulation of the tool is provided and the 80 tool handles may reinforce one another during an extracting operation, in which considerable force must be employed. Thus, when using the tool for rotating a tooth, which is obstinate, movement in the opposite 85 directions is not subject to the swing of the forceps handle in opposite directions. The jaws 12 being disposed at an angle of 45° to the general plane of the forceps may be conveniently engaged with either an upper 90 or lower tooth in any part of the mouth, while the handle portions thereof are so disposed that manipulation thereof is not interfered with.

Since it will be obvious that the construction hereinbefore set forth is capable of a certain range of change and modification without materially departing from the spirit of the invention, I do not limit myself to such specific structure except as hereinafter 100 claimed.

I claim:—

1. A forceps comprising plier connected elements each having at one end an arcuately bowed jaw bluntly tapering to a sharp 110 point, said jaws being oppositely curved and being disposed at an angle of 45° to the gen-

eral plane of the forceps, the longitudinal axes of the jaws being straight from end to end and in parallelism, the free ends of said jaws being well spaced from one another 5 when the jaws are at the limit of their closing movement.

2. A forceps comprising plier connected elements each having at one end an arcuately bowed bluntly tapering jaw, said jaws being 10 oppositely curved and being disposed at an angle of 45° to the general plane of the forceps, the longitudinal axes of the jaws being straight from end to end and in parallelism, the free ends of said jaws being well spaced 15 from one another when the jaws are at the limit of their closing movement, the handle

portion of one of said elements adjacent the pivotal connection of the elements being extended in the general direction of the axis of the forceps and having its terminal portion deflected across said axis at an angle of approximately 30° thereto, the handle portion of the other of said elements adjacent the pivot thereof paralleling the terminal portion of the handle portion of the first 20 named element and having its terminal portion substantially parallel to the axis of the forceps and provided with a hand rest, said terminal portion contacting the terminal portion of the first named handle element. 25

JOHN E. MILLER.
